VERTICAL GRAINING MACHINE

Guido von Webern and Edward William Hamant,
Dayton, Ohio, assignors to Oxford Varnish Cor-
poration, Detroit, Mich., a corporation of
Michigan

Original application November 9, 1929, Serial No.
406,018. Divided and this application August
8, 1932, Serial No. 627,818. In Great Britain
May 25, 1932

8 Claims. (Cl. 101—366)

This invention relates to an improved method and apparatus for supplying ink or pigment to substantially vertical printing elements, such as rolls. While our device may be used in any machine where it is desirable to feed ink to a substantially vertical surface, we have illustrated the device as applied to a vertical graining machine, as described in our copending application, Serial No. 406,018, filed November 9th, 1929, and 10 of which this application is a division.

In the drawings, Fig. 1 is a sectional plan view showing the general arrangement of parts of a graining machine,

Fig. 2 is a longitudinal vertical sectional view 15 thereof taken along the line 2—2 of Fig. 1, and

Fig. 3 is a transverse sectional view taken along the line 3—3 of Fig. 1.

Referring now to the drawings, the machine shown is a vertical surface graining machine 20 adapted for graining surfaces disposed vertically, or nearly so. The primary elements of the machine comprise a pattern roll 1, a transfer roll 2 and may include a pressure roll or platen 3, for carrying the work to be grained or otherwise decorated, into printing contact with the transfer roll.

At this point it may be stated that it is not essential that there be a separate pattern element such as shown, inasmuch as the pattern transfer roll 2 may have the design formed thereon. The pattern transfer element may further be embodied in shapes other than cylindrical rolls. For example, it may comprise a belt or a ribbed or grooved generally cylindrical roll adapted for impressing surfaces other than generally smooth 35 surfaces such as shown on the blank in the machine.

The elements mentioned may be supported on main machine frame members comprising, as shown, a standard 5 and a sub-base 6 carried 40 thereby in any suitable manner and secured as by bolts, not shown. The pattern and transfer roll are supported on the sub-base as will now be described.

Referring to Figs. 1, 2 and 3, the pattern roll 45 which is shown as a hollow cylinder having a central shaft 7, may have any suitable pattern thereon. For example, an intaglio pattern of a wood grain design may be etched on the outer surface in any suitable way. The shaft 7 extends 50 downwardly through a boss formation 8 on the sub-base 6 at one end and extends upwardly through an overhanging cross bar 9 secured as on posts 10 and 11, the connection to only one of these posts, namely, 10, being shown. The bar may 55 be removably secured as by hand screws, one of

which is shown at 12, Fig. 3. The lower end of the shaft 7 has associated therewith a driving arrangement for the pattern roll.

The transfer roll 2 may comprise a suitable ring of resilient material, such as congealed glue and glycerine on a suitable core 15, and has a driving shaft at 16. The driving shaft may be carried on a rocking support or frame 17 which has upper and lower arm portions 18 and 19 joined by a post 20 rising from the sub-base 6 10 and a vertical end bar 22 joining the arms 18 and 19. The purpose of the swinging mounting is so that the transfer roll may be carried out of contact with the pattern roll whenever the machine is left standing idle. The transfer roll is 15 also driven positively in the machine shown.

A description of the driving mechanism for the pattern and transfer rolls is not given here as it is fully described in our co-pending application, Serial No. 406,018. The driving mechanism for 20 the pressure roll or platen 3 is described in our copending application, Serial No. 456,337, filed May 28, 1930.

To supply pigment to the pattern roll 1, we provide a device comprising essentially, pigment 25 raising means in the nature of a pump for conveying pigment material from a reservoir to alongside the pattern roll and distribute an adequate quantity of the same uniformly on the pattern. The pigment supplying device is best shown 30 in Figs. 1 and 3, and will now be described.

In the last-mentioned figures, there is shown an ink supply tank 26 removably carried on the under side of the base member 6 as on L-shaped brackets 27, these bracket arrangements permitting the tank to be slid beneath the base member, like the drawer of a cabinet. The tank may be withdrawn from beneath the base 6 sufficiently to allow the pigment supply to be replenished, from time to time, notwithstanding the fact that, 40 as shown, the tank cannot ordinarily be fully withdrawn.

Above the pigment supply tank, the body portion 51 of the base member has an opening 102 through which extends a tube 25. The tube contains the pumping element shown as a screw 28 which lifts the pigment along the tube and spreads the pigment onto the pattern roll. The tube 25 is faced off on one side, namely, that adjacent the pattern roll, and preferably this face, designated 25'', is substantially complementary to the curve or arc of the outer surface of the pattern roll. The face 25'' is spaced apart from the pattern plate a distance determined by the thickness of the layer of pigment it is desired to place 55

on the pattern plate. This distance may be varied, as will be hereinafter shown.

The tube is supported in vertical position by a rigid arm 32 extending laterally from the tube 5 and having at one end a clamping yoke 108 embracing the post 11, which supports one end of the pattern roll supporting arm 96. The adjustment to determine the distance between the face 25" of the tube and the surface of the pattern 10 roll, may be effected by a set screw 34 supported in a suitable post 33 back of the tube, the screw 15 having its working end bearing against the tube, as shown in Fig. 3.

The pigment lifting screw 28 is preferably 15 formed, as shown in Fig. 3, wherein it will be seen that the thread faces which are uppermost are substantially flat, while the under faces of the screw threads are steeply beveled to provide a coarse thread. The screw fits the inside surface 20 112 of the tube with very little clearance, the surface of the tube being broken at one side of the tube by reason of the face 25" intersecting the cylinder on which the inside surface 112 is formed. This leaves an elongated opening substantially the length of the pattern roll through 25 which the pigment carried up by the screw is spread onto the pattern roll.

The screw 28 has a bearing at its lower end 30 which, as shown, comprises a removable apertured insert 29 of suitable bearing forming material, the aperture receiving the reduced end 116 of the screw. At its upper end, the screw has a reduced shaft portion 28' which extends through a suitable bearing insert 117 held in 35 place by a cover plate 118. At its upper end, the shaft 28' carries a spur gear 30, which meshes with a spur gear 31 surmounting and fixed to the pattern roll driving shaft 1. When the pattern roll is taken out by lifting the same upwardly, with the cross bar 96, as described, the 40 gears are simply slid out of mesh.

In a graining machine wherein the graining rolls are vertical, or nearly so, the matter of reclaiming the used pigment material presents quite 45 a problem. As shown, there is a continuous wall effect 230 rising from the base 6 and surrounding the pattern roll the transfer roll and pigment applying device. Within the wall is a substantial depression 231 which receives all the pigment 50 material scraped or otherwise ejected from the rolls and which conveys this pigment material back to the pigment supply tank 26. Preferably, the floor of the depression slopes generally toward the opening 102 through which the screw 55 tube 25 extends loosely.

To favor the discharge of used pigment toward the opening and to prevent accumulation of pigment beneath the pattern roll, the latter may have a depending wiping blade 235, as shown 60 in Fig. 3. The wiping blade is arranged to contact with the floor of the depression formed by the wall 230 to urge the pigment material lying upon the bottom of the depression toward the opening 102. The blade 235 may be arranged at 65 an angle in accordance with the rotation of the roll 1, as indicated in broken lines in Fig. 1.

The pattern and transfer rolls are equipped with scraper blades and it is highly desirable, if not essential, to reciprocate the scraper blade 70 which contacts with the pattern plate of the pattern roll so as to prevent wearing grooves in the etched surface thereof. It is practically essential to separate the scraper blade of the transfer roll from this roll whenever the machine is left standing 75 idle so as to prevent the scraper blade from

leaving a permanent depression in the transfer roll surface.

The scraper blades are shown at 40 and 41, but further description is omitted here, as they are fully described in our co-pending application, 5 Serial No. 406,018.

The platen or pressure roller 3 may be supported adjacent the transfer roll by a swingable arm 100. The arm may be pivotally mounted at 105 on the frame 5. The free end of the arm 10 may be provided with a suitable handle 107.

While we have shown in detail a machine operating on the offset printing principle; that is to say, with a pattern roll carrying a primary pattern element, the etched plate, and a transfer 15 roll for taking the pigment from such pattern roll, it is obvious that, insofar as the general arrangements are concerned, the transfer or "composition" roll may carry the pattern. In such event, the pigment applying device would 20 operate directly on the transfer roll and the pattern roll would be omitted.

We claim:

1. A mechanism for supplying ink material to a substantially vertical printing member, comprising means for feeding the material along a vertically extending tube adjacent the periphery of the member and means for spreading the material directly from the tube on the member through side opening in the tube. 30

2. An apparatus for supplying liquid pigment material to a substantially vertical graining roll, comprising a vertically extending tube having an opening in its side wall, means for feeding the material upwardly within said tube adjacent the 35 roll and spreading the material directly on the roll through the side opening in the tube.

3. In a graining machine, a graining roll arranged on a substantially vertical axis, means for driving the roll, a pigment supply device comprising a container for pigment, a tube alongside said roll and means to force pigment from the container along the tube, the tube having a slotted elongated vertical opening adjacent the roll through which the forced pigment is spread 45 onto the roll. 40

4. A pigment applying device for a graining roll, comprising, a pigment conveying tube adapted to be positioned adjacent the roll substantially parallel to the axis thereof, said tube having an 50 elongated through opening in the side thereof adjacent the roll and having a widened face adjacent the opening substantially parallel to the general roll surface, means to adjust said face toward and away from the roll, and means to 55 force pigment material along the tube.

5. In a graining machine, wherein there is a substantially vertical pattern roll, pigment supply means below the roll, a tube having one end communicating with said pigment supply, a lift 60 screw in the tube, and means for driving the screw, the tube having an opening adjacent the roll through which the pigment material is spread directly onto the pattern roll.

6. A pigment-applying device for a graining 65 roll, comprising a pigment-conveying tube adapted to be positioned adjacent the roll and substantially parallel with the axis thereof, said tube having an elongated opening in the side wall thereof, said tube being so positioned that the 70 periphery of the roll projects into and substantially closes the opening in said tube, and means to force pigment material along the tube.

7. A pigment-applying device for a graining 75 roll, comprising a pigment-conveying tube adapt-

ed to be positioned adjacent the roll substantially parallel with the axis thereof, said tube having an elongated slot in its side walls, the walls of the slot being substantially parallel with the axis of the roll and arcuately shaped to substantially conform with the general contour of said roll.

8. A pigment-applying device for a graining roll, comprising a pigment-conveying tube adapt-

ed to be positioned adjacent the roll substantially parallel with the axis thereof, said tube having an elongated opening through the side thereof adjacent the roll, means to adjust said tube toward and away from the roll, and means to force 5 pigment material along the tube.
